ARTIFICIAL SKI SURFACE

Marion G. Randazzo, Inglewood, Calif., assignor to Karen Supply Co., Inc., Chino, Calif., a corporation of California

Filed July 5, 1966, Ser. No. 562,894

4 Claims. (Cl. 94—13)

ABSTRACT OF THE DISCLOSURE

An improved artificial ski surface is disclosed which is composed of a plurality of individual structural members, each of which is provided with a plurality of elongated plastic pins extending from one side thereof and each of which has at one edge a pair of male flanged tabs and on the opposite edge a pair of mating female sockets. The individual structural elements are interlocked to form an artificial ski surface.

This invention relates to an artificial ski slope structure and more particularly is concerned with an injection moldable plastic structural member capable of being overlappingly interlocked to provide a unitary surface closely approaching that of normal snow in its ski response.

Many structures and means have been proposed as substitutes for a ski surface, including machine made ice, straw or nonwoven flocking, sand, and individual plastic pads containing a plurality of individual flexible projections. The latter, which may have the general cross-sectional configuration shown in FIGS. 4 and 5, and do not form a part of my invention, are extremely difficult to employ for a ski surface structure. These plastic pads have been in use in an extremely limited manner for several years. Even though the surface provided by this structure responds to skis in a manner similar to that of snow, it is not a practical, commercial structure since it is not one which can be applied in an efficient manner to a sloped surface of any significant size. In those few instances where it has been used, it has been applied by securing each individual structure to the base surface by nailing each piece, adjacent to another piece, to such surface.

In a 7-acre ski slope, utilizing sections 6" square, approximately 1,250,000 individual sections are required to cover the surface. It will be apparent that nailing each of such segments to the base wood surface at each of the four corners is such a time consuming job that the labor requirements for constructing a ski slope are sufficiently great to make the resulting ski slope a commercial impracticality. Especially is this true where the adjacent elongate protuberant plastic pins are as close as they need be to provide a relatively uniform ski surface. In this case, and in view of the length of pins required, the task of nailing the elements to the base requires a degree of dexterity and care that further increases the amount of labor necessary to apply them.

The use of nails to tie the sections to the base surface is disadvantageous for still another serious reason. Impact loads on individual sections or groups of sections resulting from falls tends to cause the nails to be pulled out, leaving them partially extended or lying loose on the surface. The hazard to subsequent skiers is apparent. Serious injuries can be so caused.

It is therefore an object of my invention to provide an improved, artificial plastic ski surface composed of a plurality of overlappingly interlocked, plastic segments, each of which has a ski support surface comprised of a large plurality of elongated plastic pins.

It is a further object of my invention to provide an artificial ski slope structural member having a plurality of elongated plastic pins extending from one side thereof and having at one edge a pair of male flanged tabs and

2

on an opposite edge thereof a pair of mating female sockets.

It is another object of my invention to provide an improved artificial ski surface comprised of a plurality of plastic structural members having a large plurality of elongate plastic resilient pin elements protruding from one side thereof and opposed pairs of mating male and female flange tabs and sockets interlockingly secured to each other and adhesively secured to a smooth permanent surface constructed of concrete, wood or other material.

I further desire to provide a rapid, economic method of constructing an artificial ski surface.

These, as well as further objects of my invention will become apparent from a consideration of the following disclosures as related to the drawings in which:

FIG. 1 is a top plan view of a portion of a ski surface illustrating a plurality of the structural surface members of my invention in interlocking, overlapping engagement;

FIG. 2 is an enlarged fragmentary top plan view of one of the structural plastic members illustrating the female socket member;

FIG. 3 is an enlarged fragmentary top plan view of a segment of one of the structural plastic members illustrating the male, flanged tab locking elements;

FIGS. 4 and 5 are cross-sections taken on the lines 4—4 and 5—5 of FIG. 2;

FIGS. 6, 7, 8 and 9 are cross-sections taken on the lines 6—6, 7—7, 8—8, and 9—9 of FIG. 1;

FIG. 10 is a cross-sectional view taken through a pair of mating interlocking lug members during the process of locking one structural element to its adjacent element; and

FIG. 11 is an enlarged fragmentary top plan view of three adjacent, overlapping, interlocked, structural elements of my invention.

Referring to FIG. 1, it will be seen that the artificial ski surface is composed of a plurality of identical members, identified for ease of reference by the numerals 1 through 7. As shown, the elements are generally square in plan view. However, they can take any suitable rectangular shape. Each of the elements 1—7 has a substantially flat base 8 from which the elongate pins 9 and 10 project. The pins are integral with the base member and are generally of conical shape; the base portion being of greater diameter than the end portions. As will be apparent from FIGS. 4 and 5, the pins 9 and 10 of the structure shown are of different lengths. This is for the purpose of providing two different ski support surface levels; one defined by the tops of the pins 10 and the other defined by the tops of the pins 9. The result of use of a plurality of different surface levels is to provide for increased response of the surface to the skis when they are turned and banked with respect to the upper surface. Nevertheless, the provision of a plurality of different surface levels for the ski base is not critical, is not part of my invention and all of the pins could be of substantially the same height without departing from my invention.

The elongate pins 9 and 10, being made of a plastic, resilient material provide a surface which not only has minimal frictional sliding resistance but which is sufficiently resilient to "give" to at least a certain degree, when a skier falls accidentally.

As illustrated, each of the ski surface elements 1—7 is provided with a peripheral edge 11 which is generally free of the pin projections 9 and 10 and which essentially constitutes an extension of the base 8 of such element. It will nevertheless be seen that the peripheral edge 11 is a discontinuous one; being composed of a plan view, L segment 12, whose upper face is substantially on the same plane as the upper face of base 8, but which is substantially half the thickness of the base 8 in order to provide a step recess 13. The peripheral edge 11 is also composed of a similar plan view, L seg-

ment 14 which, however, has its lower surface substantially in the plane of the lower surface of base 8, and which is similarly substantially one half the thickness of the base 8 in order to provide a step recess 15. As seen in FIG. 9, when two of the elements 1-7 are placed in adjacency, the L segment peripheral edge 12 overlays the peripheral edge L segment 14 and presents a relatively smooth upper and lower surface. As will be seen in FIGS. 1 and 11, eliminating the corner segments 16 and 17 at opposite diagonal corners permits three adjacent members to overlap without having an excess thickness of the sheet of which base 8 is composed at the corners.

The foregoing described elements are substantially similar to the elements which have previously been used to construct a ski slope in Japan, except that the edges of such elements have been provided with a plurality of holes through which nails could be driven in order to secure such element to a wood base surface.

However, as above disclosed, the employment of nails to secure such elements to a wood surface not only presents an unacceptable hazard to skiers in the event of partial extraction of the nail, but also requires excessive labor to accomplish installation of the number of units generally required for construction of a ski slope.

In accordance with my invention, a pair of tabs 19 are formed integrally with and extend laterally from the outer peripheral edge of the element. These tabs are provided with substantially perpendicularly, upwardly extending flange 20.

Directly oppositely disposed from the tabs 19 on the opposite edge of elements 1-7, is a pair of sockets 21. These sockets may, in their simplest form, comprise rectangular openings 22, which extend partly along the edge of the elements 1-7, and partly inwardly thereof. A flange 23 extending perpendicularly from the surface of the base 8 provides a restraining flange for the flange 20 on the tabs 19. The flange 23 forms one leg of an inverted cross sectionally, U-shaped housing 24. The other flange-leg 25 of this housing is integral with the base 8 and forms, with the segment 26 and end segments 27 and 28, a housing that is completely closed except for its base side.

It will be noted that the upper segment 26 of housing 24 itself forms a base from which the elongate pins 29, 30 and 31 extend. The socket 21 is thus constructed in such a manner as to not only retain and secure the tabs 19 against escape but to permit the surface formed by the pins to be continuous in the area of the housing. In addition, the housing substantially eliminates the presence of openings through the base material and thereby reduces water seepage or flow from the top surface of the base 8 through to the base material of the slope.

The manner of securing of adjacent elements 7 is illustrated in sequence in FIGS. 6 and 7, 10 and 8. A single row of elements, such as those indicated as elements 1 and 2 in FIG. 1, is secured with adjacent edges overlapping in the manner illustrated in FIG. 9 by applying a suitable adhesive to the under surface of base 8 and placing the elements on the concrete or wood base material at the very top of the slope. Assuming that element 2 is the end of a row in the top leftmost section of the hill, adhesive is applied to the undersurface of element 3 and it is then tilted upwardly as shown in FIG. 10 and the opening between flange 23 and end segment 18 is placed in a position to receive the flange 20 of tab 19. Element 3 is then tilted down until it contacts the concrete or wood base surface. Adhesive is similarly applied to the element 4 and this member is then positioned in such manner as to have its sockets 21(a) and 21(b) receive and retain the flange tabs of adjacent elements 1 and 2. The same procedure is followed with respect to elements 5 and all the adjacent elements and then with the third row of elements beginning with element 7, as will be evident. Sufficient adhesive may be placed on

the under surface of each of the elements in the area of the sockets 21 to form an extremely tight lock between adjacent ski surface structural elements 1-7.

The provision of pairs of mutually interlocking means 5 on the opposite edges permits the distribution of stresses, resulting from a skier falling in one area, amongst a great number of adjacent elements and thus reduces the possibility of such element being pulled from the surface.

I prefer to install my ski surface structural elements 10 as above disclosed. Placing the flanged tab 19 in a direction facing down the slope permits the elements to be installed in such a manner that the peripheral edge 11 of the uppermost element overlaps the element immediately below it. This reduces the amount of water that 15 can pass through to the concrete or wood base surface and increases the over-all stability of the structure.

A further aspect of my invention resides in constructing the male tabs 19 smaller in both directions in a horizontal plane than the corresponding female sockets 21. 20 This size relationship permits adjacent interlocking elements to be skewed with respect to one another thus permitting the elements in a long row which follows a compound hill curvature to be interlocked with the elements in the next adjacent row. Without the loose-fit 25 provided by such size differences, the misalignment of adjacent rows of elements caused by variations in slope contour would cause progressive difficulty in interlocking such rows; to the ultimate extent that certain of the tabs would be impossible to mate with their corresponding 30 sockets.

It will also be seen that utilizing opposed pairs of mating interlocking means on opposite edges of each of the 35 elements permits construction of a substantially integral ski slope surface since each member is interlocked to each other member through these means. Although I have described my invention with reference to a particular 40 interlocking means along opposite edges of the ski surface elements, it will be evident that other interlocking elements can be provided that will serve the desired function.

I claim:

1. An artificial ski surface comprising a structural, substantially smooth base and a plurality of plastic rectangular elements adhesively secured to said base, said elements having protruding from one face thereof a plurality of elongate resilient pins, the ends of said pins defining a relatively low friction ski surface, each of said elements having a plurality of male interlocking means integral with an edge thereof and having a plurality of female socket means integral with the opposite edge thereof corresponding to the location of said male interlocking means 45 and lockingly mating therewith, said male interlocking means on each of said elements engaging the female socket means on two adjacent elements whereby substantially all of said plurality of plastic elements are interlocking engaged with one another through said male and female means, said male interlocking means comprising a tab and an integral flange projecting therefrom in the direction of said pins and said socket means comprising a rectangular opening in said element spaced from the edge thereof and a cross sectionally rectangular housing integral with said element and projecting in the direction of 50 said pins and covering a rectangular portion of said opening whereby said tab extends through said opening and said flange interlocks within said housing, wherein the edge of said element in which said opening is provided is of less thickness than the remainder of said element and wherein the edge of said element to which said tab is secured is of less thickness than the remainder of said element and is upwardly stepped to provide a recess to overlap the edge of adjacent elements.
2. The ski surface of claim 1 wherein said male interlocking means is smaller than the opening defined by said socket means to provide a loose fit therebetween whereby adjacent rows of said elements may be interlocked when said rows are placed on a surface with a compound curvature.

3. In an artificial plastic ski surface element having a rectangular base sheet and a plurality of elongate resilient pins integrally formed therewith and protruding from one surface thereof, the ends of said pins defining a relatively low-friction ski surface, the improvement comprising a plurality of male interlocking means integral with an edge of said element and a plurality of female socket means integral with said element along the opposite edge thereof and corresponding to the location of said male interlocking means, wherein said male interlocking means comprises a tab and an integral flange projecting therefrom in the direction of said pins and wherein said socket means comprises a rectangular opening in said element spaced from the edge thereof and a cross-sectionally rectangular housing integral with said element and projecting in the direction of said pins and covering a rectangular portion of said opening whereby said element can be interlockingly engaged to a similar element, and wherein the edge of said element in which said opening is provided is of less thickness than the remainder of said element and wherein the edge of said element which said tab is secured is of less thickness than the remainder of

said element and is upwardly stepped to provide a recess to overlap the edge of adjacent similar elements.

4. The improvement in the ski surface structural element of claim 3 wherein said male interlocking means is smaller than the opening defined by said socket means to provide a loose-fit therebetween.
